(57) **CLAIM**

I claim the ornamental design for a watch face, as shown and described.

DESCRIPTION

The FIGURE is a top side view of the watch face of the claimed design.

The surface of the watch face shown in the FIGURE is flat and planar.

The broken lines showing a watch band and knobs are for the purpose of illustrating the environment in which the design is used and form no part of the claimed design.

1 Claim, 1 Drawing Sheet(56)
